United States Patent Office.

W. R. THOMAS, OF CATASAUQUA, PENNSYLVANIA.

Letters Patent No. 79,029, dated June 16, 1868.

IMPROVED CAR-WHEEL.

The Schedule referred to in these Letters Patent and making part of the same.

TO ALL WHOM IT MAY CONCERN:

Be it known that I, W. R. THOMAS, of Catasauqua, in the county of Lehigh, and State of Pennsylvania, have invented new and useful Improvements in Car-Wheels; and I do hereby declare that the following is a full, clear, and exact description thereof, which will enable others skilled in the art to make and use the same, reference being had to the accompanying drawings, forming part of this specification.

My invention relates to improvements in car-wheels made of cast metal, whereby it is designed to provide a more durable wheel, and which is less liable to be affected by unequal contraction or expansion than any now in use.

And it consists in a more improved form of the wheel, whereby the metal is disposed in a manner better calculated to secure the aforesaid objects, as will be more fully described on reference to the accompanying drawings, wherein—

Figure 1 represents a side elevation of my improved wheel, and

Figure 2 a section on the line $x x$ of fig. 1.

Similar letters of reference indicate corresponding parts.

In casting my improved wheel, I arrange the mould and provide a core so as to form a hollow enlargement around the hub, as shown at A, and hollow arms, B, communicating with the said hollow enlargement, and running outward to the tread, and a thin webbing of metal between the said arms, also connecting with the rim and the said enlargement.

I have found very great advantages resulting from the above-described disposition of the metal of cast-metal wheels, in the respect of great strength, and freedom from liability to crack from unequal contraction and expansion in cooling, when cast.

I claim as new, and desire to secure by Letters Patent—

A cast-metal car-wheel, provided with the hollow enlargement A, hollow arms B, communicating with the same, and the in-turning thin metal webbing, all constructed and arranged substantially as and for the purpose described.

The above specification of my invention signed by me, this 20th day of March, 1868.
